UNITED STATES PATENT OFFICE.

ARTHUR HEATON, OF LIVERSEDGE, ENGLAND.

LOOM SHUTTLE-BOX.

SPECIFICATION forming part of Letters Patent No. 768,900, dated August 30, 1904.

Application filed June 29, 1903. Serial No. 163,564. (No model.)

To all whom it may concern:

Be it known that I, ARTHUR HEATON, residing at Liversedge, in the county of York, England, have invented certain new and useful Improvements in Loom Shuttle-Boxes; and I do hereby declare the following to be a full, clear, and exact description of the invention, such as will enable others skilled in the art to which it appertains to make and use the same.

10 This invention relates to shuttle - boxes formed of bent sheet metal; and it consists in the novel construction of the same, as hereinafter fully described and claimed.

15 In the drawings, Figure 1 is a plan view of the main part of the shuttle-box before being folded to shape. Fig. 2 is a plan view of the shuttle-box after being folded to shape. Fig. 3 is a front view of the shuttle-box. Fig. 4 is a cross-section taken on line A B in Fig. 3.

20 The main portion *a* of the shuttle-box is stamped out of sheet metal, as shown in Fig. 1, and is then bent upon the lines *b* and *c*, so that it takes the form shown in Fig. 4. This shuttle-box has three shelves *h* and four compartments for the shuttles. A plate *d* is secured to the front of the box at one end, and the "swell" is hinged to this plate. A plate *e* is secured to the front of the box at its other end and has lugs *f* for the pin which limits 25 the outward movement of the swell. Slots *g* are cut parallel to each other in the back of the box, one for each compartment, and one compartment has a slot or opening *g'*, which is formed between the doubled portions 2 of the sheet *a*. One compartment, 3, is formed by bending the plate *a* into a loop, and the parts

2 are formed by doubling the plate upon itself at each side of the loop. The remaining compartments 4, 5, and 6 are formed by bending the sheet above and below the compartment 3. The opening *g'* is parallel with the openings *g* and is similar to them. These slots *g* and *g'* form openings for the picker to work in. The slots *g* and *g'* are preferably cut in the box after it is bent to shape; 45 but they may be cut in the blank (shown in Fig. 1) before bending it, if desired. Four shuttle - compartments are shown and described; but this invention is not confined to a shuttle-box having that number of compartments. 50

The plate *e* has holes *i* for lightening it, and *j* represents metal wearing-strips secured to those parts of the box which slide in the frame of the loom.

55

What I claim is—

A shuttle - box having its main portion formed of a sheet-metal plate provided with a rectangular loop which forms one shuttle-compartment, portions of the said plate being bent 60 double at the back of the said compartment and a space being left between them to form a slot for the picker, and the remaining shuttle-compartments being formed by bending the said plate above and below the said loop 65 into similar compartments.

In testimony whereof I affix my signature in presence of two witnesses.

ARTHUR HEATON.
